United States Patent Office.

WILLIAM ENNIS, OF HUDSON, NEW JERSEY.

Letters Patent No. 60,867, dated January 1, 1867.

IMPROVEMENT IN FURNACES.

The Schedule referred to in these Letters Patent and making part of the same.

TO ALL WHOM IT MAY CONCERN:

Be it known that I, WILLIAM ENNIS, of Hudson, in the county of Hudson, and State of New Jersey, have invented a certain new and useful Improvement in Furnaces, of which the following is a full, clear, and exact description, reference being had to the accompanying drawing, forming part of this specification, and in which—

Figure 1 represents a longitudinal sectional elevation of a furnace constructed according to my improvement; and

Figure 2, a transverse section thereof, taken as indicated by the line $z z$ in fig. 1.

Like letters indicate like parts in both figures.

My improvement has reference more particularly to that description of furnace described in Letters Patent of the United States issued to Joseph Hindle, assignee of Ferdinand Braun, bearing date May 17, 1864, in which a basket grate is used, composed of two inclined sections and a horizontal section with side channels for supplying the inclined sides of the grate with fuel, such as coal dust, saw dust, or other similar or refuse materials. The purpose to which the furnace is to be applied is immaterial; it being equally suited to domestic as to manufacturing uses, whether for heating steam boilers or otherwise.

The economy resulting from the use of fuel of the character here mentioned is well understood, but there are difficulties which occasionally arise that require to be met to make the employment of such fuel advantageously available. Thus, in burning very fine fuel of this description, say, the fine refuse of sifted "coal dust," as it is termed, there is then an unfitness in the present construction of grates, that is, in the basket form, made with round holes or perforations in its inclined sides; as these openings, if large, allow the coal dust to fall through and be wasted, while, if very small, they choke and interfere with the combustion. To obviate this defect is the object of my improvement, which has for its end the obtainment of a large grate area or air space between the bars of the inclined sides of the grate with but little or no tendency, however, for the coal or other dust, however fine, to fall or pass through, nor yet of it to choke the grate. I use for this purpose, in connection with side supply passages or openings feeding the fuel from above, a basket grate, in which the bars of the inclined sides are made up of slats arranged after the manner of steps, somewhat similar to the mere disposition of the slats in the grates of a totally different character, and preferably make said slats to prevent a downward inclination of their faces in an inward direction, which serves to prevent the dust from lodging on the slats, and, in connection with air chambers outside of said inclined sides, creating a draught through between the bars, effectually tends to prevent choking.

Having thus described in full the nature of my invention, the following description of it with reference to the accompanying drawing will suffice to further and fully explain the same.

A are the furnace walls, which are or may be extended to form a drying-chamber, B, for the fuel arranged over the arch C of the grate, and which from its shape will serve to distribute the powdery fuel equally, or thereabouts, to both sides of the grate by apertures $\alpha \alpha$, which may be opened and closed, and have their discharge regulated by means of slides or other devices. The arch, C, may also serve as a reflector, to aid the combustion of the fuel. D is the basket grate; E, its flue opening; and F, a fire door opening for inserting any suitable combustible material on starting the fire or ignition of the coal dust fed by the apertures α , after which said opening may be closed. The inclined sides of this grate are made up of closely arranged slats, $b b$, one above the other, in step fashion, and preferably inclining downward in an inwardly direction, so that while the fuel, in passing on to the grate by the apertures α has its fall broken by the step construction of the grate, which largely contributes to its combustion, the inclined position of the slats, aided, too, by air rushing from back or side air chambers, G, provided with inlets, c , serves effectually to prevent choking of the grate, the side bars or slats of which give a wide distribution and large area of air space between them to effect combustion of the fuel, while there is but little or no tendency to choke or of the fuel falling through the interstices of the slats or bars which constitute the sides of the grate. Thus, the slatted sides of the grate, supplied as described, possess advantages which do not ordinarily attach to other slatted grates for burning fuel of a different character. The lower or horizontal portion, d , of the grate, which communicates with the ash-pit, S, below, may be of ordinary construction.

What I claim herein as new and useful, and desire to secure by Letters Patent, is—

The combination of the basket grate with its sides made of overlapping slats, as described, air chambers G, and supply apertures $\alpha \alpha$, constructed and arranged substantially as and for the purpose or purposes herein specified.
